(57) **CLAIM**

The ornamental design for a food holding bin as shown and described.

DESCRIPTION

FIG. 1 is a perspective view of the first embodiment of a food holding bin showing our new design.

FIG. 2 is an elevational view of a front side thereof.

FIG. 3 is an elevational view of a rear side thereof.

FIG. 4 is a top plan view thereof.

FIG. 5 is a bottom plan view thereof.

FIG. 6 is an elevational view of a right side thereof.

FIG. 7 is an elevational view of a left side thereof.

FIG. 8 is a perspective view of the second embodiment of a food holding bin showing our new design.

FIG. 9 is an elevational view of a front side thereof.

FIG. 10 is an elevational view of a rear side thereof.

FIG. 11 is a top plan view thereof.

FIG. 12 is a bottom plan view thereof.

FIG. 13 is an elevational view of a right side thereof; and, FIG. 14 is an elevational view of a left side thereof.

The broken lines in the drawings depict portions of the food holding bin that form no part of the claimed design.
